ELECTRIC RAZOR

Bernd Rohrbach, Kettenhofweg 80,
Frankfurt am Main, Germany

Filed Jan. 20, 1971, Ser. No. 108,239

Claims priority, application Germany July 24, 1970

Term of patent 14 years

Int. Cl. D28—03

U.S. Cl. D95—3

Fig. 1

Fig. 2

Fig. 3

FIG. 1 is a side elevational view of an electric razor, showing my new design, the appearance being the same from all sides;

FIG. 2 is a top plan view; and

FIG. 3 is a bottom plan view thereof.

I claim:

The ornamental design for an electric razor, as shown and described.
